UNITED STATES PATENT OFFICE.

EDWARD M. COOK, OF OBERLIN, OHIO.

METALLIC PACKING.

No. 873,507.

Specification of Letters Patent.

Patented Dec. 10, 1907.

Application filed May 29, 1907. Serial No. 376,302.

To all whom it may concern:

Be it known that I, EDWARD M. COOK, a citizen of the United States of America, residing at Oberlin, in the county of Lorain 5 and State of Ohio, have invented new and useful Improvements in Metallic Packings, of which the following is a specification.

This invention relates to certain new and useful improvements in metallic packings, 10 and particularly to metallic packings of that type comprising a cage or casing provided with interior grooves or cavities to receive packing rings to bear upon a piston rod.

The object of the invention is to provide 15 a metallic packing having means arranged therein for catching the water formed by condensation of steam and discharging the same through a suitable outlet, and also having a novel construction and arrangement 20 of parts by which formation of the condensation outlet is permitted without weakening the casing.

With these and other subordinate objects 25 in view, the invention consists of the novel features of construction, combination and arrangement of parts hereinafter fully described and claimed, reference being had to the accompanying drawing, in which:—

Figure 1 is a side elevation and partial 30 longitudinal section through a metallic packing embodying my invention. Fig. 2 is an outer end view of the packing, showing the piston rod in transverse section.

Referring to the drawing, 1 represents a 35 longitudinally divided casing, provided at its outer end with a bolting head or flange 2 and also provided upon its interior with a series of annular grooves or cavities 3, in which the packing rings 4 are held when the 40 two sections of the casing are secured together, said packing rings preferably being of the sectional type and held yieldingly in contracted condition by encompassing coiled springs 5.

The outer groove or cavity of the series 3 45 is somewhat shallower in depth than the remaining grooves or cavities of such series, and the packing ring held therein is arranged to serve as a barrier against the escape of the 50 water of condensation from the outer end of the casing. Formed within the casing between said outer groove or cavity and the next adjacent groove or cavity is a catch basin, groove or recess 6, which may be 55 either segmental or annular in form, accordingly, as the packing is arranged horizontally

or vertically in order to provide for the effective collection of the water of condensation.

The gutter 6 communicates with an outlet 60 passage 7 of L-form, one portion of which extends radially out from the gutter between the outer end cavities of the series 3, while the other portion extends longitudinally of the casing and connects at its inner end with 65 the outer end of the radial portion and at its outer end with an internally threaded recess 8 formed in the face of the head or flange 2, said recess being threaded for connection with an exhaust pipe through which the water 70 of condensation discharges.

It will be observed that the longitudinal branch of the passage 7 accordingly extends partially between the outer surface of the casing and the shallow outer end groove or 75 cavity, the shallow form of the cavity leaving a sufficient thickness of metal between it and the outer surface of the casing to provide for the formation of the passage 7 in the manner described without weakening the 80 casing, in which respect the construction is superior to one in which the outer end of the casing is formed with an enlarged cavity to catch the water of condensation, requiring a reduction in thickness of the casing, whereby 85 the latter is weakened at a point whereon the greatest amount of strain falls from the pressure or thrust resulting from the reciprocatory motion of the piston rod.

In the operation it will be understood that 90 the metallic packing rings prevent the escape of steam from the cylinder around the piston rod, but are ineffective in preventing the flow of water caused by the condensation of the steam. Hence the water of condensation 95 passing the packing ring arranged in the cavity on the inner side of the gutter 6 will flow into said gutter and thence discharge through the passage 7 into the waste pipe. The arrangement of this gutter between the 100 outer packing ring arranged in the shallow cavity and the next adjacent ring disposed on the inner side of said cavity prevents the escape of the water of condensation past said first named ring, so that the full amount of 105 water will discharge through the outlet passage. By this means the casing will be effectually drained of the water of condensation without in any manner interfering with the operation of the packing rings and without weakening any of the parts of the packing. 110

Having thus described the invention, what is claimed as new, is:—

1. A metallic packing comprising a casing provided with a series of internal cavities, 5 the outer cavity of the series being shallower than the other cavities, and packing rings arranged in said cavities, the casing also being provided between the shallow cavity and the next adjacent cavity with a condensation outlet extending radially from the piston space to a point beyond said shallow cavity and thence longitudinally past said outer cavity through the outer end of the casing.
2. A metallic packing comprising a casing 10 provided with a series of packing ring cavities, the outer cavity of the series being shallower than the others, a gutter between said shallow cavity and the next adjacent cavity, and a condensation drain outlet of L-form, having a portion extending radially outward 20 from said gutter between said adjacent cavities to a point beyond the cavities and thence longitudinally of the casing and through the outer end thereof.

In testimony whereof, I affix my signature 25 in presence of two witnesses.

EDWARD M. COOK.
